UNITED STATES PATENT OFFICE

170,203

TELEVISION ANTENNA

Ralph N. Leonard, Crystal Lake, Ill.

Application May 1, 1953, Serial No. 24,794

Term of patent 7 years

(Cl. D26—14)

To all whom it may concern:

Be it known that I, Ralph N. Leonard, a citizen of the United States and a resident of Crystal Lake, county of McHenry, and State of Illinois, have invented a new, original, and ornamental Design, for a Television Antenna, of which the following is a specification, reference being had to the accompanying drawing, forming a part thereof, in which Fig. 1 is an elevational view of a television antenna showing my new design, and Fig. 2 is a top view thereof.

I claim:

The ornamental design for a television antenna, substantially as shown.

RALPH N. LEONARD.
